[57] CLAIM

The ornamental design for a front panel for a storage device, as shown and described.

DESCRIPTION

FIG. 1 is a top front and side perspective view of a front panel for a storage device showing our new design the undisclosed side bottom and rear views are unornamented; and,

FIG. 2 is a front view thereof.

The broken lines are shown in the views for illustrative purposes only and form no part of the claimed design.

FIG. 1

FIG. 2
